UNITED STATES PATENT OFFICE

CHARLES W. DAKE, OF CHICAGO, ILLINOIS, ASSIGNEE TO CHICAGO MANUFACTURING COMPANY, OF CHICAGO, ILLINOIS, A CORPORATION OF NEW JERSEY.

COMMUTATOR AND HOLDING MEANS THEREFOR.

1,236,243.

Specification of Letters Patent.

Patented Dec. 8, 1917.

Application filed September 31, 1917. Serial No. 193,465.

To all whom it may concern:

Be it known that I, CHARLES W. DAKE, a citizen of the United States, residing at Chicago, in the county of Cook and State of Illinois, have invented a certain new and useful Improvement in Commutators and Holding Means Therefor, of which the following is a specification.

My invention relates to improvements in commutators and holding means therefor and has for one object to provide a new and improved structure whereby a commutator may be held rigidly and permanently in position on the rotor shaft. Another object is to provide means for supporting and reinforcing the commutator so that it will not fly out of position or be distorted under high speed conditions. Another object is to provide a commutator which will be stiff and rigidly held in position without undue length. Another object is to provide a commutator which will be reinforced and held in position from the inside and which will have an unobstructed outer surface extending from end to end. Other objects of my invention will appear from time to time in the specification.

My invention is illustrated more or less diagrammatically in the accompanying drawings, wherein—

Figure 1 is a longitudinal section through a commutator end of an electric machine;

Fig. 2 is a section along the line 2—2 of Fig. 1;

Fig. 3 is a section similar to Fig. 1 showing a modified form wherein the commutator is held at four places instead of three.

Like parts are indicated by like characters in all the figures.

A is the rotor shaft. It carries the usual armature A¹ rotating in a field A² and is mounted at its outboard end in a bearing A³ supported on a bracket A⁴. All this is the usual electric machine construction.

B is a base sleeve adapted to be slidably placed in position on the shaft and to abut the shoulder B¹. B² is a nut screw-threaded on the end of the shaft A adapted to engage the opposed end of the sleeve B and when tightened to lock it in position. The sleeve B is flanged at its inboard end as at B³ and this flange is cut away, dovetailed, or tapered as at B⁴. B⁵ is a commutator mounted on the base sleeve B made up of a plurality of

separate wedge-shaped commutator bars B⁷ 55 insulated from one another by mica strips B⁸ and each one having an inwardly extending locking portion B⁹ tapered at one end to engage the taper B⁴ and at the other to engage a central holding sleeve. These 60 commutator segments are brought together as indicated into a unit to form a cylindrical whole and the locking members are so proportioned that there is just room between them and the base sleeve B for the insulating material B⁵ which also extends over the tapers at either end of the locking members. This insulating material is also carried from the base of the locking members forwardly and rearwardly so that it is inter- 70 posed between the commutator and the central locking sleeve. It will be observed that the commutator itself is enlarged to permit entrance of the central locking sleeve but the relative size of the parts is such that the 75 commutator seats snugly on the insulating material interposed between it and the several supporting and locking sleeves.

C is a central holding sleeve which fits snugly on the sleeve B and is adapted to fit snugly within the enlarged portion of the commutator. It is tapered as indicated to engage the taper on the commutator and it in turn carries an outer holding sleeve C¹ tapered as at C² to engage an outer taper 85 on the outboard end of the commutator. The sleeve C is screw-threaded at C³ and engaged by an outer lock nut C⁴ adapted to thrust the outer sleeve inwardly and the sleeve B is screw-threaded at C⁵ engaged by 90 the central lock nut C⁶ adapted to thrust the sleeve C inwardly. The lock nuts B², C⁴ and C⁶ are all of them separate in their operation and never engage one another. C⁴ is put on first, C⁶ next and then B² and they 95 are then tightened up inversely, first B², then C⁶ and then C⁴ to lock the parts successively in position and hold the commutator on it.

D D are brushes adapted to engage the 100 commutator in the usual manner being supported by conducting arms D¹ and provided with a binding post D² to which lead the usual conductors D³ whence the current is controlled in the usual manner not here indicated.

In the modified form shown in Fig. 3 I have shown two central locking sleeves. The

commutator instead of being made with two varying interior diameters is made with three. The smallest diameter engages the base sleeve, the next largest diameter engages the larger sleeve, the next diameter engages a still larger sleeve. These two sleeves each of them engage tapers of different diameters on the inside of the commutator so that the commutator bars are each of them held down at two points intermediate their ends. This ordinarily would not be necessary but in the event of the large machine or machine traveling at exceedingly high rotational speeds it might be desirable 15 to have four or even more points of anchorage on the commutator bars instead of three as indicated in my preferred form.

It will be evident that while I have shown in my drawings an operative device, still 20 many changes might be made both in size, shape and arrangement of parts without departing materially from the spirit of my invention and I wish, therefore, that my drawings be regarded as in a sense diagrammatic.

The use and operation of my invention are as follows:—

A commutator made up of alternate sections of mica for insulating and copper to 30 form the conductor and previously bored out and shaped as indicated in the drawing is forced by the operator on to the sleeve on the end of the commutator shaft. This sleeve is provided with the inner taper to 35 overhang and engage the taper or hook on the inside of the inner end of the commutator. The operator then slips on the central holding sleeve which has a central taper to overhang a central taper on the commutator. He then slips on the outer holding sleeve which is slidably mounted on the inner sleeve. He then starts the outer holding nut which is screw-threaded on the center sleeve and he then after the outer holding nut is in place screws the center holding sleeve nut in position. This is followed by the master nut which holds the base sleeve in position. This first nut is screwed up tight to jam the base sleeve firmly against 45 the shoulder on the shaft and hold it steady. Then the center sleeve is tightened up by rotation of the central end. This operates to force the inboard and central tapers on the commutator rigidly against the hook 50 portions overhanging them. The commutator is now held in position at two points, then the outer nut is tightened and the outer sleeve forced in place to engage the outer taper thus holding the commutator at three 55 points. This is screwed down tight so that the commutator is first clamped at its inner end and at its center. The outer nut is then screwed up so that the commutator is clamped at its outer end.

60 65 This gives three annular holding zones one

at either end and one at the center of the commutator and makes it impossible for the commutator segments to bend or become displaced even at the highest rotational speeds.

It will be understood, of course, that the 70 commutator bars themselves have little if any independent strength. They are made of soft copper or other conducting material and bend or give with comparative facility. It is this that makes it so important to hold 75 them rigidly in position and it is necessary that the holding means be applied to the inside because otherwise the working surface is broken up and sparking on the part of the brushes is likely to ensue. It might be 80 possible to substitute for the separate sleeve and nut a sleeve with a nut integral therewith but, of course, while simplifying the manufacture of the sleeve and nut the soft 85 commutator bars might be damaged by the rotation of the sleeve engaging them.

I claim:—

1. A commutator comprising a hollow cylindrical body having a plurality of different internal diameters and a plurality of tapers 90 associated therewith, a plurality of sleeves of different diameters upon which the commutator body is mounted said sleeves having each of them one taper in opposition to one of the tapers on the commutator body, separate and independent means for forcing each of said sleeves longitudinally against the commutator body to lock the tapers together.

2. A commutator comprising a hollow cylindrical body having a plurality of different internal diameters and a plurality of tapers associated therewith, a plurality of sleeves of different diameters upon which the commutator body is mounted said sleeves having each of them one taper in opposition to one of the tapers on the commutator body, 100 separate and independent means for forcing each of said sleeves longitudinally against the commutator body to lock the tapers together said means comprising a plurality of nuts screw-threaded on said sleeves adapted to engage the ends thereof.

3. A commutator comprising a base sleeve flanged and having a taper, a commutator 115 body mounted thereon and having a taper in opposition to the taper on the flange, a central locking sleeve mounted slidably on the base sleeve the commutator body being enlarged to permit penetration of the locking sleeve and provided with a taper intermediate its ends at the inner portion of the enlargement the sleeve being provided with a taper to engage the opposed taper on the commutator, a nut screw-threaded on the 120 base sleeve adapted to force the inner sleeve against the taper the outer end of the commutator body being tapered, a sleeve slid- 125 able on the central sleeve taper in opposition to the outer taper and a nut screw- 130

- threaded on the central sleeve adapted to force the outer sleeve against the commutator body.
4. A commutator comprising a hollow cylindrical body having a plurality of different internal diameters, and a plurality of tapers associated therewith a plurality of supporting sleeves of different diameters upon which the commutator body is mounted, said sleeves having each of them one taper in opposition to one of the tapers on the commutator body, a plurality of said commutator engaging supporting sleeves adapted to be inserted into the commutator body from the same direction.
5. A commutator comprising a hollow cylindrical body having a plurality of different internal diameters, and a plurality of tapers associated therewith, a plurality of supporting sleeves of different diameters upon which the commutator body is mounted, said sleeves having each of them one taper in opposition to one of the tapers on the commutator body, a plurality of said commutator engaging supporting sleeves adapted to be inserted into the commutator body from the same direction, separate and independent means for forcing each of said sleeves longitudinally against the commutator body to lock the tapers together.
6. A commutator comprising a hollow cylindrical body having a plurality of different internal diameters, and a plurality of tapers associated therewith, a plurality of supporting sleeves of different diameters upon which the commutator body is mounted, said sleeves having each of them one taper in opposition to one of the tapers on the commutator body, a plurality of said commutator engaging supporting sleeves adapted to be inserted into the commutator body from the same direction, separate and independent means for forcing each of said sleeves longitudinally against the commutator body to lock the tapers together, said means comprising a plurality of nuts screw threaded on said sleeves adapted to engage the ends thereof.
7. A commutator comprising a hollow cylindrical body having a plurality of different internal diameters, and a plurality of tapers associated therewith, a plurality of supporting sleeves of different diameters upon which the commutator body is mounted, said sleeves having each of them one taper in opposition to one of the tapers on the commutator body, a plurality of said commutator engaging supporting sleeves adapted to be inserted into the commutator body from the same direction, separate and independent means for forcing each of said sleeves longitudinally against the commutator body to lock the tapers together, said means comprising a plurality of nuts screw threaded on said sleeves adapted to engage the ends thereof, each sleeve being locked directly to the sleeve disposed diametrically next within it.

In testimony whereof I affix my signature, in the presence of two witnesses, this 70
14th day of September, 1917.

CHARLES W. DAKE.
